UNITED STATES PATENT OFFICE.

JOHN F. MCKENNA, OF PROVIDENCE, RHODE ISLAND

THIMBLE FOR BOILER-FLUES.

1,220,438.

Specification of Letters Patent. Patented Mar. 27, 1917.

Application filed June 9, 1915. Serial No. 33,001.

To all whom it may concern:

Be it known that I, JOHN F. MCKENNA, a citizen of the United States, and resident of the city of Providence, in the county of Providence and State of Rhode Island, have invented certain new and useful Improvements in Thimbles for Boiler-Flues, of which the following is a specification.

This invention relates to thimbles of the character used more particularly for the protection of the exposed ends of boiler flues, and the object of this invention is to provide such a thimble that may be formed complete by an automatic operation to be readily applied to the flue of a new boiler to serve as a reinforcement and protection of its exposed ends to materially prolong the life of the boiler.

Then again a number of these devices may be carried in every engineer's repair kit and may be employed where quick action is necessary to make a temporary repair on old boilers by forcing the thimbles into the end of a leaky tube to expand and tighten the same.

A further object of the invention is to provide a greatly enlarged outwardly turned flange on this thimble which is adapted to cover and protect the exposed end of the flue from the direct action of the fire in the fire box.

A further object of the invention is to taper the outer surface of the body portion of this thimble so that as it is forced into the boiler flue it will expand and tighten the same in the flue plate.

A still further object of the invention is to taper the body of the thimble on its inner surface drawing the same down to a thin entering edge so that there will be no shoulder on the inside of the tube and so effectually prevent the gathering and lodging of sediment, soot or other foreign substances at its end the effect of which deposit is to cause rust and corrosion at this point which soon destroys the tube.

With these and other objects in view, the invention consists of certain novel features of construction, as will be more fully described, and particularly pointed out in the appended claims.

In the accompanying drawings:

Figure 1— is a sectional side elevation showing a portion of a boiler with the tubes 55 entering the fire box, showing the tube ends

as being exposed to the direct action of the fire.

Fig. 2— is a sectional side elevation showing a portion of the flue plate with the flue passing therethrough and being secured therein also showing one of my improved flue thimbles as having been forced into one of the tubes and permanently secured therein by expanding the body portion thereof.

Fig. 3— is a face view of a flue plate showing the general staggered arrangement of flues and the protecting effect of a plurality of my improved thimbles upon the exposed face of this flue plate.

Fig. 4— is a sectional side elevation showing a detail of my improved flue thimbles ready to be positioned in a tube.

In the construction of thimbles of my improved character, a section of soft iron may be drawn and struck in a swaging machine, or otherwise formed into a short tubular body 10 having an outwardly extending flange 12 at one end, the body portion having an outer surface which is slightly tapered toward its entering edge 11, for the purpose of entering the tube and expanding and tightening the same in its flue plate as the thimble is driven into the flue. This outwardly turned flange 12 is preferably 80 grooved on its inner face 13 to fit over the bead 14 on the end of the tube which extends through the flue plate 15. The outer surface of this flange is preferably rolled back over the bead 14 so as to provide a 85 uniform thickness of flange and effectually protect the bead. The inner surface 16 of the tube is formed somewhat tapering and is reduced down to a thin edge at 11 so that when this thimble is in position in the 90 tube no shoulder whatever will be left to permit the lodging of foreign substances 95 therebehind. This thimble may be formed of soft sheet iron stock so that it can be readily drawn or formed into the desired 100 shape and after being positioned in the flue tube may be rolled and expanded to lock the same therein when desired.

In the construction of a fire tube boiler the law requires that the tubes shall pass 105 through the flue plate and be rolled over, flanged or beaded on the outside of the plate. By this construction, it is found in practice that the tubes of a boiler will last from six months to three years according to its uses 110

and particularly according to the chemical properties of the water in the boiler.

In some of the Western States the water is of such a nature as to eat out the flues in 5 a very short time. In the running of locomotives and marine boilers and the like it is often found of particular advantage to the engineers when a leaky tube is discovered to be able to make temporary repairs so as to 10 complete the trip without drawing the fire and still maintain the full capacity of the boiler. Another important advantage of the invention is that the bead 14 is absolutely protected from the flames of the fire box, 15 so that burning off of the bead is prevented and the thimble is so shaped that a minimum surface is exposed to the action of the flames so that danger of burning off of said thimble is greatly reduced.

20 To accomplish such a repair my improved thimble may be passed by a bar into position in the tube and forced home thus expanding the tube and effectually stopping the leak and later when the boiler can be 25 spared from its regular service the repair may be made more permanent by expanding the thimble in its tube in the manner illustrated at 17 in Fig. 2.

One cause of leaky tubes is that the heat 30 from the fire box acts directly upon the exposed ends of these tubes, which burns and causes them to break and crumble.

It will be noted that by my improved construction, I have provided an enlarged 35 flange 12 which will completely cover, inclose and protect the exposed end of the tube and prevent them from leaking and so greatly prolong the active life of the boiler.

Another feature of this invention is that 40 by making the flange of a large diameter it

not only protects the beaded end of the flue, but also reinforces and protects the exposed surface of the flue plate and so again serves to prolong the life of this portion of the boiler. Then again when a crack appears in the flue plate between the flue ends by the insertion of a number of my improved thimbles about the crack the heads reach over the ruptured surface so that the rupture is nearly closed and this as above 50 described can be done without drawing the fire from the boiler.

My improved thimble is an article complete in itself adapted to be formed at the very minimum expense complete by automatic machinery and ready to be instantly applied and positioned by the attendant, a hammer being the only tool required.

The reduction in expense of manufacture is an item to be considered in a device of 60 this character owing to the fact that large numbers may be used as each boiler contains hundreds of tubes.

I claim:

The combination with an end wall of a 65 boiler, and a flue of uniform thickness and diameter having one end extending through said wall and provided with a bead engaging the wall, of an exteriorly tapered tubular thimble driven into the tube to expand 70 the same, the inner end of said thimble having a thin edge, the outer end of the thimble having an annular flange of substantially the same thickness as the thicker portion of the body of the thimble, said flange 75 being free of substantial projections, and engaging and covering said bead, whereby burning off of the bead is prevented.

In testimony whereof I affix my signature.

JOHN F. MCKENNA.
